UNITED STATES PATENT OFFICE.

BURELL S. SMITH, OF PUEBLO, COLORADO.

MUD-CHAIN HOOK.

1,334,322.

Specification of Letters Patent. Patented Mar. 23, 1920.

Application filed April 5, 1919. Serial No. 287,687.

To all whom it may concern:

Be it known that I, BURELL S. SMITH, a citizen of the United States, residing at Pueblo, in the county of Pueblo and State of Colorado, have invented new and useful Improvements in Mud-Chain Hooks, of which the following is a specification.

This invention relates to mud chain hooks and particularly to devices of this sort to be applied on truck and other motor vehicle wheels to form the connection for chains attached around the tread.

An object of my invention is to provide a device of this character which is constructed to be readily applied to a wheel, and which has the chain receiving and holding portions thereof disposed to retain the chain in a position to give a maximum grip.

A further object resides in arranging a spring in conjunction with the hook proper, which spring guards against accidental displacement or loosening of the chain.

Another object lies in providing spring holding means to lock and retain the spring in place, said means however being constructed to releasably secure the spring so that it may be removed and replaced, should occasion demand.

With these and other objects in view, which will be apparent from the drawing, specification, and claims, this invention includes novel features of construction and combinations of parts which will now be set forth.

In the drawings:

Figure 1 is a view in elevation of a wheel showing the application of my invention thereto.

Fig. 2 is a sectional view taken transversely through a wheel felly and tire, and illustrating my invention with a chain applied thereto.

Fig. 3 is a view in elevation of my invention.

Fig. 4 is a plan view of the showing in Fig. 3.

Fig. 5 is a sectional view on line 5—5 of Fig. 3.

The body portion 1 has the ends thereof reduced and then bent or otherwise shaped to form chain receiving hooks 2 and 3, these chain receiving hooks being preferably

tapered toward their extremities so that, as particularly shown in Fig. 3, the bend from the body portion swells or extends somewhat beyond the end of the hook, the object of which formation will be later set forth.

On the upper side of the body portion 1, and substantially midway between hooks 2 and 3, an enlargement or standard 4 is formed. This standard has a groove or slot 5 formed therethrough in line with hooks 2 and 3, and this groove is dovetailed at its edges at 6.

The body portion 1 is made of such length that the hook portions will extend slightly beyond the felly of a wheel, and the bolt receiving openings 7 and 8 are provided on opposite sides of standard 4 to receive bolts 9 by which the device is secured upon the felly of the wheel.

A spring clip 10, shaped substantially as shown in Fig. 4, is made of a width and thickness to catch within the dovetailed edges of groove 5 when this spring is inserted endwise into the groove, and of a length sufficient that the ends thereof extend over and bear upon the ends of hooks 2 and 3. The ends of the spring are preferably reduced to have substantially the same width as the ends of the hooks, and the length of the spring is gaged to avoid extension beyond the tops of the hooks. Through this shaping of the spring, and through the provision of the swell at the bends from the body to the hooks, the spring is protected and there is little likelihood of trash or the like fouling in the wheel and engaging the spring to raise the ends from engagement against the ends of the hooks.

While spring 10 would doubtless remain in place under ordinary circumstances through its own resiliency, it is preferable that provision be made for locking and positively retaining the spring against displacement. A laterally extending groove 11 is provided in the top of the standard and a screw-threaded bore 12 is formed in this last mentioned groove and outside of the line of groove 5. A screw 13, having a wide head, is provided to be turned into the threaded bore 12, in which setting the head overhangs and locks upon the middle portion of spring 10 to secure the spring in

place. By this arrangement spring 10 is clamped against endwise movement and secured within the groove of standard 4 with the ends thereof bearing resiliently against the ends of hooks 2 and 3.

My improved mud chain hook is adaptable to all classes of truck and motor wheels, and in the application of the device one or several of the chain hooks will be secured transversely on the felly of the wheel, as shown in Figs. 1 and 2. A section of chain 14, of proper length, is looped around the tire or tread of the wheel and end links of the same are fitted over hooks 2 and 3. In placing the chain, spring clip 10 is raised at one end and an end link of the chain is fitted on the hook thus cleared, the chain then being carried over the tire of the wheel to the opposite side where the opposite end of spring clip 10 is raised and the free end of the chain is caught upon the remaining hook. If desired two sections of chain can be secured by a single device, as shown in Fig. 1. Other chains with different forms of links can be attached in the same manner, and even a rope can be applied without altering the hook.

While, in the foregoing, I have described specific embodiments and have suggested only certain possible adaptations in use, it will be appreciated that my purpose is to provide a hook structure by which a chain or rope is held in position to accomplish the desired function, and which hook is constructed to secure the rope or chain from jostling off or accidental displacement, in view of which it is to be understood that in practice I do not limit myself to such specific details as herein set forth, but may

resort to modifications within the scope of 40 the claims.

I claim:

1. A mud chain hook including with an elongated body portion to be secured on the felly of a wheel and having chain hooks at 45 the ends thereof, said body having a standard midway between said hooks and said standard provided with a dovetailed slot in line with the hooks, a spring clip inserted endwise within said slot and having its ends 50 bearing resiliently in contact with the points of said hooks.

2. A mud chain hook including with an elongated body portion to be secured on the felly of a wheel and having chain hooks at 55 the ends thereof, said body having a standard midway between said hooks and said standard provided with a dovetailed slot in line with the hooks, a spring clip inserted endwise within said slot and having its ends 60 bearing resiliently in contact with the points of said hooks, and a screw carried by said standard at one side of the slot therein to be turned down and clamp against said spring clip to secure the same against end- 65 wise removal from the slot.

3. With a chain holding hook having a slot, a spring clip to be inserted endwise into said slot and bear resiliently in contact with the point of the hook, said spring 70 clip being notched in that portion received within the slot, and a screw to be set to clamp said spring clip and received in the notch thereof to retain said clip against displacement.

In testimony whereof I affix my signature.

BURELL S. SMITH.
